CAR CONSTRUCTION

Edward Payson Smith, Winnetka, Ill., assignor to Illinois Railway Equipment Co., Chicago, Ill., a corporation of Illinois

Filed Feb. 11, 1963, Ser. No. 257,578
10 Claims. (Cl. 308—137)

This invention relates, generally, to the construction of railway cars and it has particular relation to devices for lubricating the center plates at the ends of a railway car.

Among the objects of this invention are: To provide in a new and improved manner for reducing the friction between the juxtaposed surfaces of railway car center plates; to provide for this purpose a mixture of non-ferrous metal particles and lubricant packaged in such manner as to facilitate the application thereof to the center plates; to employ for receiving the mixture of non-ferrous metal particles and lubricant a carrier plate having cavity providing means thereon which are formed of materials that not only disintegrate on being subjected to the pressure incident to normal operation of the center plates but also on disintegration function as a lubricant with the metal particles being worked into the juxtaposed surfaces of the center plates and forming bearing surfaces thereon whose coefficient of friction is substantially less than that of the material forming the center plates themselves.

In the drawings:

FIG. 1 is a vertical sectional view taken through a car body center plate and a portion of a cooperating truck bolster, both devices being of conventional construction and the arrangement showing the application of the lubricator of this invention between the surfaces of the center plates.

FIG. 2 is a bottom plan view of the car body center plate.

FIG. 3 is a top plan view of the central portion of the truck bolster which shows the center plate.

FIG. 4 is a view, similar to FIG. 3 but at an enlarged scale, and showing the application of one form of the lubricator of the present invention thereto.

FIG. 5 is a vertical sectional view, at an enlarged scale, to show the first fold that is made in the plastic bag which provides the cavity in one embodiment of this invention.

FIG. 6 is a view, similar to FIG. 5, and shows the second fold that is made.

FIG. 7 is a top plan view of a modified form of lubricator.

FIG. 8 is a vertical sectional view, at an enlarged scale, taken generally along the line 8—8 of FIG. 7.

FIG. 9 is a top plan view of still another modification of the lubricator.

FIG. 10 is a vertical sectional view taken generally along the line 10—10 of FIG. 9.

Referring now particularly to FIG. 1 of the drawings, it will be noted that the reference character 10 designates, generally, the car body center plate that usually is formed of cast steel. The center plate 10 has a depending central section 11 that is provided with a downwardly facing annular bearing surface 12 which also is shown in FIG. 2. A central opening 13 extends through the car body center plate 10 for receiving a center pin 14 that is supported at its lower end in a socket 15 which is formed integrally with a truck bolster, shown generally at 16, and formed in conventional manner of cast steel. The truck bolster 16 has a central opening 17 through which the center pin 14 extends. Surrounding the central opening 17 is an upwardly facing annular bearing surface 18 on the truck bolster 16 which also is shown in FIG. 3. That portion of the truck bolster 16 which includes the annular bearing surface 18 constitutes a center plate and is so referred to herein. An inner annular flange 19 surrounds the cen-

2

tral opening 17 and extends above the level of the bearing surface 18. An outer annular flange 20 extends along the outer periphery of the annular bearing surface 18 and, with the inner annular flange 19 forms an annular groove for receiving the depending central section 11 of the car body center plate 10.

Difficulty has been encountered in providing a proper lubricant between the annular bearing surfaces 12 and 18. Since the bearing pressure is the order of 1,000 pounds per square inch, it has been difficult to provide adequate lubrication. Because of this these bearing surfaces become scored with the result that the coefficient of friction thereof is extremely high. Difficulty is encountered in relative rotation between the car body center plate 10 and the truck bolster 16 particularly when the car is moving along a curved portion of the track. Because of this there is a tendency for undue wear to take place along the flanges of the car wheels.

In accordance with this invention a lubricating device, indicated generally at 22, is interposed between the bearing surfaces 12 and 18. It is shown in detail in FIG. 4. Here it will be observed that the lubricating device 22 includes a carrier plate 23 that may be formed of plastic material such as polyethylene. The carrier plate 23 has a central opening 24 for receiving the inner annular flange 19 for the purpose of allowing the carrier plate 23 to lie flatwise against the upwardly facing annular bearing surface 18 on the center plate portion of the truck bolster 16.

A plurality of bags 25 provide cavities for receiving a mixture 26 of non-ferrous metal particles and a relatively heavy lubricant. The bags 25, preferably four in number, are formed of plastic material such as polyethylene which, together with the lubricant in the mixture 26 on disintegration, provides an additional lubricating effect.

For illustrative purposes it is pointed out that each bag 25 has the mixture 26 in the cavity provided thereby comprising one ounce of grease and one and one-half ounces of brass drillings. Other copper base non-ferrous materials can be employed instead of brass drillings which have been found to be highly satisfactory. The lubricant can be a grease containing about twelve percent graphite and preferably is a zero grade grease having a viscosity at 100° F. of Saybolt #441. Another satisfactory grease is a Crater compound comprising heavy residual mineral oil having a viscosity at 210° F. of Saybolt #300. This also may be identified as a number 3 grade grease.

The bags 25 as they are obtained from the bag manufacturer are heat sealed along one end as indicated at 27. After the mixture 26 of non-ferrous metal particles and lubricant has been inserted in the cavity provided by a bag 25, the other end is folded first as indicated at 28 in FIG. 5 and then, as indicated in FIG. 6, a second fold is made as indicated at 29. This arrangement of the folds 28 and 29 effectively prevents the escape of the contents of the bag 25. If desired, the second fold 29 can be heat sealed. However, since the bag 25 must be secured to the plastic carrier plate 23, such heat sealing of the second fold 29 can be dispensed with. Instead the ends of the bags 25, closed in the manners indicated, are placed, as shown in FIG. 4, on the upper surface of the carrier plate 23 and then are secured thereto by staples 30, there being two at each end. If desired, the ends of the bags 25 can be heat sealed to the carrier plate 23. However, it has been found that it is more economical to use the staples 30.

In operation a lubricating device 22 is positioned on the upwardly facing annular bearing surface 18 with the car body center plate 10 having been removed therefrom. It will be understood that a lubricating device 22 is applied to each of the two truck bolsters 16 at each end of the car. After making certain that the center pin 14 is in position, the car body is lowered into place with the car

body center plate 10 being positioned as shown in FIG. 1. Here it will be observed that the downwardly facing annular bearing surface 12 initially engages the upper sides of the plastic bags 25 containing the mixture of non-ferrous metal particles and lubricant. Because of the relatively high unit pressure thus exerted, the bags 25 are ruptured and the material forming them and the material forming the carrier plate 23 is disintegrated and thoroughly mixed with the mixture 26 of non-ferrous metal particles and lubricant. Experience has shown that the non-ferrous metal particles fill the pores in the bearing surfaces 12 and 18 and, in effect, plate out thereover to form relatively smooth non-ferrous bearing surfaces which require far less lubricant than do the bearing surfaces 12 and 18 by themselves. The inner and outer annular flanges 19 and 20 act to retain the mixture comprising the disintegrated carrier plate 23 and bags 25 together with the mixture 26 of non-ferrous metal particles and lubricant. Tests have shown that the lubricating device 22, constructed as described, materially prolongs the life of the center plates and maintains a relatively low coefficient of friction therebetween. As a result there is less wear of the wheel flanges and improved operation of the trucks of the car.

FIGS. 7 and 8 show a modification of the present invention. Here the reference character 32 designates, generally, a lubricator which comprises a carrier plate 33 of suitable plastic material which may be polyethylene. The carrier plate 33 is provided with a central opening 34 for receiving the inner annular flange 19 that surrounds the bearing surface 18, FIG. 1. Cavities in the form of pods 35 are vacuum formed in the carrier plate 33. As shown, they may be circular in configuration and are relatively shallow. After the pods 35 are filled with a mixture 36 of non-ferrous metal particles and lubricant, as described above, they are closed by covers 37 that may be rectangular in shape and heat sealed at 38 along their periphery to the carrier plate 33.

The application and functioning of the lubricator 32 to the center plates of the railway car is the same as described above for the lubricating device 22.

FIGS. 9 and 10 show still another embodiment of the present invention. Here it will be observed that the reference character 41 designates, generally, a lubricator. It includes a carrier plate 42 of plastic material such as polyethylene. It has a central opening 43 to receive the inner annular flange 19 on the truck bolster 16 as shown in FIG. 1. A shallow annular grooved section 44 is vacuum formed in the carrier plate 42 for the purpose of providing a cavity for receiving the mixture 45 of non-ferrous metal particles and lubricant. After the mixture 45 has been inserted in the curved section 44 an annular cover 46 of plastic, such as polyethylene, is positioned over it and then it is heat sealed as indicated at 47 and 48 along its inner and outer edges to the carrier plate 42.

Various other thermoplastic materials can be employed instead of polyethylene for the carrier plates 23, 33 and 42, for the bags 25 and for the covers 37 and 46. For example, where suitable, any of the following thermoplastic materials can be employed:

Polyvinyl chloride
Polyvinyl acetate
Cellulose acetate
Cellulose butyrate
Cellulose triacetate
Cellulose nitrate
Saran (polyvinylidene chloride)
Pliofilm (rubber hydrochloride)
Nylon (polyamide)
Acrylic
Cellophane (re-generated cellulose)
Polyethylene
Polystyrene
Teflon (polytetrafluoroethylene)
Mylar (polyester)

Poly vinyl alcohol Polypropylene

What is claimed as new is:

1. In combination:
  - (a) upper and lower railway car center plates,
  - (b) a center pin extending between said center plates,
  - (c) a carrier plate between said center plates having a central opening to accommodate said center pin,
  - (d) cavity providing means on said carrier plate, and
  - (e) a filling of a mixture of non-ferrous metal particles and lubricant in said cavity providing means.
2. The invention, as set forth in claim 1, wherein the carrier plate and cavity providing means are formed of materials that disintegrate upon being subjected to pressure incident to the normal operation of the center plates.
3. The invention, as set forth in claim 2, wherein the non-ferrous metal is a copper base material.
4. The invention, as set forth in claim 1, wherein the cavity providing means comprises a plurality of individual containers secured to the carrier plate.
5. The invention, as set forth in claim 4, wherein the containers comprise a plurality of bags.
6. The invention, as set forth in claim 4, wherein the containers comprise pods integral with the carrier plate with an overlying cover secured thereto.
7. In a railway car construction in combination:
  - (a) upper and lower cast metal center plates having annular juxtaposed bearing surfaces and characterized by the application of relatively high unit pressure by said upper center plate to said lower center plate, and
  - (b) at least one plastic package of a mixture of non-ferrous metal particles and lubricant interposed between said center plates characterized by being ruptured and the contents dispersed due to said pressure whereby said bearing surfaces have said plastic, metal particles and lubricant distributed in the form of a lubricating film thereover, the distribution of said metal particles being facilitated by said lubricant.
8. The invention, as set forth in claim 7, wherein the pressure is sufficient to work the metal particles into the pores of the bearing surfaces of the cast metal center plates and provide juxtaposed bearing surfaces of non-ferrous metal.
9. A lubricator for installation between the center plates of a railway car having a center pin extending therethrough comprising:
  - (a) a carrier plate having a central opening to accommodate the center pin,
  - (b) cavity providing means on said carrier plate comprising a shallow annular grooved section therein and an annular cover secured to said carrier plate, and
  - (c) a filling of a mixture of non-ferrous metal particles and lubricant in said cavity providing means.
10. The invention, as set forth in claim 1, wherein the material forming the cavity providing means and the filling are characterized by being capable of disintegration under the pressure applied between the center plates and being distributed over the juxtaposed surfaces thereof as a result of their relative rotation.
